UNITED STATES PATENT OFFICE

PAUL A. DINSMOOR, OF LAWRENCE, KANSAS, ASSIGNOR TO LAWRENCE PAPER MANUFACTURING COMPANY, OF LAWRENCE, KANSAS, A COPARTNERSHIP COMPOSED OF THE M. G. BOWERSOCK TRUST, IRVING HILL, PAUL A. DINSMOOR, HORTENSE B. HILL, AND MARY B. DINSMOOR

REVERSIBLE REEL FOR STRIP-APPLYING MACHINES

Original application filed May 12, 1926, Serial No. 108,556. Divided and this application filed August 13, 1928. Serial No. 299,356.

My invention relates to reels, and more particularly to apparatus for supporting a web in functioning relation with a machine into which the web is drawn incidentally to operation of the machine, for example a reinforcing strip adapted to be applied to box blanks along their lines of scoring to strengthen the blanks where they are ordinarily weakened by scoring and to provide means on which the sections of the blanks may hinge when being formed into boxes or cartons, the present application being a division from my co-pending application, Serial No. 108,556, filed May 12, 1926, wherein the present invention was illustrated as applied to a lining machine.

In operating a machine supplied with a web, the web reel becomes exhausted and a new reel must be applied. The machine must be stopped while the end of the web on the new reel is being attached to the end of the web in the machine, or otherwise introduced into the machine. The principal object of my invention therefore, is to reduce to a minimum the retardation in operation of the machine due to the necessity for introducing a fresh web.

Further objects of the invention are to facilitate the adjustment of strip-supporting reels in relation to fixed positions toward which the strips are to be drawn, and renewal of reels.

It is further a particular object of the invention to facilitate the mounting of strip reels in relation to a lining machine and the renewal of strips being fed to the machine, and the invention will be described as adapted for application of reinforcing strips to sheets of board simultaneously with the application of the lining to the board, it being understood that the invention can be used in conjunction with other machines than the lining machine mentioned.

In accomplishing these and other objects of the invention, I have provided improved details of structure, the preferred forms of which are illustrated in the accompanying drawings, wherein:

Fig. 1 is a perspective view of reels and a reel support embodying my invention and

portions of a lining machine to which the invention is applied for illustrative purposes.

Fig. 2 is a longitudinal sectional view of a strip reel arm and its mounting on the line 2—2, Fig. 1.

Fig. 3 is a section on the line 3—3, Fig. 2.

Fig. 4 is a detail perspective view of a type of reel which I prefer to employ.

Referring in detail to the drawings:

1 designates a supporting standard illustrated as being mounted on a machine which may be a lining machine generally indicated by a roller 2 adapted to act on a strip of corrugated board 3. 4 designates a bracket supported by the standard, and 5 and 6 bracket arms mounted respectively on the bracket 4 and a part 7 of the machine. The arms 5 and 6 are connected at their outer ends by a clamp 8 for a reel arm shaft 9, and the standard and shaft-supporting elements being duplicated for supporting the shaft.

Rotatably mounted on the shaft 9 is a reel arm 10 which may be duplicated along the shaft suitably for a particular purpose for example as many times as there are reinforcing strips to be applied to a board, and but one of these will be referred to, as a description of it applies equally to all of the others.

The arm 10 comprises a pair of bars 11 having circular enlargements 12 intermediate their ends and spaced by a hub collar 13 having flanges 14 secured to the enlargements 12 by rivets 15, the outer ends of the bars being free to provide for ready insertion of reinforcing strip reels therebetween.

Each of the arms is rotatable on an individual bushing 16 which is keyed to the shaft 9 by splines 17 which extend throughout the length of the shaft, so that all of the reel arms that may be employed are held to the shaft by the same pair of splines, the bushing having end flanges 18 lying along the sides of the arm and being locked against longitudinal displacement on the shaft by set screws 19 which extend through the flanges 18 to contact with the splines, the splines providing flat surfaces for engagement by the ends of the set screws.

The arm 10 is adapted to extend at an

80

85

90

95

100

angle to the horizontal, to hold the reinforcing strip reel on its upper end in proper position for feeding a strip to the machine, the arm being held in such set position by a plunger lock operable in a housing 20 secured to the hub 13 by screws or the like 21 and within which the plunger shank 22 is slidably mounted. On the inner end of the shank is a plunger 23 adapted for projection through an aperture 24 in the hub 13 into one of a plurality of sockets, and preferably into either of two diametrically opposite sockets 25 or 26 in the bushing 16.

Fixed to the inner end of the base of the housing 20 is a cup 27, within which the inner end of the plunger may work, and surrounding the cup and the outer end of the plunger and bearing against the base of the cup and against a ring flange 28 on the plunger is an expansion spring 29, whereby the plunger is yieldably projected in the direction of the shaft 9.

The outer end of the shank 22 carries a handle 30 whereby the plunger may be withdrawn against the tension of its spring.

With this arrangement the arms may be set on the shaft in position to properly support a reel of reinforcing strip and, when desired, the arm may be released to pivot on the shaft and relock in position after it has made a half turn, so that the opposite end of the arm is in the position for supporting a reel of reinforcing strip in functional position.

The reinforcing strip is wound and stored in a roll with a hole in the center thereof to permit the insertion of the reel. When the reel is inserted, the roll of reinforcing strip material can be easily and quickly applied to the carrying arm.

The reel for carrying the strip comprises a hub 31 of a length to fit snugly between the bars 11 of the arm 10 and is preferably formed in two separate halves. One of the halves comprises a sleeve 32 having a bore adapted to fit snugly over a pin 33 having a head 34, the pin being adapted for projection through apertures 35 and 36 in the respective arm bars 11. The sleeve is of such length as to fit snugly between the bars, and one end has an extended flange 37 to which is secured a reel flange 38.

The other half of the reel comprises a sleeve 39 adapted to telescope over the sleeve 32 of the other half of the reel and of less length than the sleeve 32 so that one end of the sleeve may bear against the inner face of the flange 38, the opposite end having a flange 40 carrying the reel flange 41, the reel flanges corresponding in diameter to properly contain the wound strip of reinforcing material 42.

The reel is locked in place on the arm by a cotter pin 43 which is adapted for projecting through an aperture in the end of the pin

opposite the head 34 and attached to the reel arm by a chain or the like 44 to prevent its loss or displacement when the reels are being changed.

Supported between the standards 1 is a pan 45, and the reel is above the pan in functional position. The reel arm is dimensioned and arranged for suitable relation to the machine for example to overlie and rotate above the sheet 3 of corrugated board as it is forwarded through the machine.

Rotatably mounted in the standards 1 and revoluble within the pan 45 is a moistening or gluing roller 46, and rotatably mounted in the standards 1 above the roller 46 is a guide roller 47 for holding the strip of reinforcing material to the roller 46 and guiding it in the same direction as the board.

In using the invention, any number of strips may be provided, having any desired relations with each other as to size, character, position and delivery, and suitable means are employed for drawing the strips from the reels. In describing the invention I will assume that four strips are provided of similar size and character for simultaneous delivery, and that the machine is adapted to draw the strips from the reels. The selective positions for the strips having been determined, the arms are adjusted on the shaft 9 to the proper spaced relation, the bushings of the several arms locked to the shaft by the set screws 19, the arms set by the plunger locks, and reels of strips mounted in the upper ends of the arms, the strips being threaded between the rollers 46 and 47.

The reels of the respective strips will become exhausted, and new reels must be supplied. I anticipate emptying of the reels by applying similar reels to the lower ends of the arms 10 before the strips have been exhausted from the upper reels, it being apparent that the fresh reels may be applied to the lower ends of the arms without interfering with feed from the upper reels.

As the upper reel or reels become nearly exhausted, it is only necessary for me to pull the plungers which lock the arms to the shaft, turn the arms about until the fresh reels are at the top and the nearly empty reel or reels at the bottom, the reinforcing strip feeding into position from either top or bottom position of the reels, and then connect the ends of the fresh strips to the ends of the strips exhausted from the previous reels, so that feed of the strips may continue as before. This interchanging of reels may be effected without material, if any, interruption in the operation of a main machine and consequently little, if any, time is lost in the process of renewal of the reinforcing strips, the interchanges of full reels for empty ones being made from time to time as necessity demands, so that a full reel is always on one end of each arm ready for use when the active reel

on the other end of the arm has been exhausted.

It is apparent also that the means for fixing the arms 10 in selected position permit great flexibility in adjustments which is enhanced by the provision of the plurality of arms splined on the shaft, and the plurality of outwardly extending portions of the arms.

What I claim and desire to secure by Letters Patent is:

1. In a reeling device of the character described including a shaft, a shaft support and a plurality of reel-supporting arms, means for mounting the arms slidably on the shaft, and latching means including a member engaged with said mounting means to restrain the arms collectively against rotation and a plurality of members supported respectively by said arms and engageable with said mounting means for individually latching the arms in selected positions with reference to the shaft.

2. In a reeling device of the character described including a shaft and a shaft standard, a reel support including a bushing slideable on the shaft and latched thereon against rotation, a hub rotatable on the bushing, a reel arm fixed to the hub, and means for latching the hub to the bushing.

3. Apparatus of the character described, comprising a shaft, an arm comprising a bushing adjustable on the shaft, a hub rotatable on the bushing, bars extending oppositely from the hub, means for anchoring the hub in either of two positions on the bushing, and means at the ends of the bars for rotatably supporting a reel.

4. In apparatus of the character described, a shaft, a bushing splined on the shaft, means for anchoring the bushing against longitudinal movement on the shaft, a hub rotatable on the bushing, means for anchoring the hub in either of two positions on the bushing, bars extending oppositely from the hub and reels removably mounted on the outer ends of the bars.

5. In apparatus of the character described a shaft, a bushing splined on the shaft, means for anchoring the bushing against longitudinal movement on the shaft, an arm rotatable on the bushing comprising a hub member and opposite extensions on the hub member, a plunger mounted on the hub member and engageable in the bushing to lock the arm to the bushing, and means on opposite ends of the arm for mounting a reel.

6. In apparatus of the character described, a shaft, a bushing splined to the shaft, means for fixing the bushing in longitudinally adjusted position on the shaft, an arm comprising a hub rotatable on the bushing and having a pair of spaced bars at opposite sides of the shaft for receiving a reel therebetween, a reel removably mounted between the bars, the bushing having diametrically opposite sockets

and the hub having an aperture for registration with either of the sockets, a plunger housing on the hub, a plunger within the housing projectable through the hub opening into either of the bushing sockets and means 70 yieldingly projecting the plunger to lock the arm against rotation on the shaft.

In testimony whereof I affix my signature.

PAUL A. DINSMOOR.
